UNITED STATES PATENT OFFICE.

JOHN T. F. BAEYERTZ, OF LOS ANGELES, CALIFORNIA.

STAMP-STICKER AND ENVELOP-SEALER.

No. 921,059.

Specification of Letters Patent.

Patented May 11, 1909.

Application filed November 10, 1908. Serial No. 461,973.

To all whom it may concern:

Be it known that I, JOHN T. F. BAEYERTZ, a citizen of the United States, residing at Los Angeles, in the county of Los Angeles 5 and State of California, have invented a new and useful Stamp - Sticker and Envelop-Sealer, of which the following is a specification.

This invention relates to a device for moistening and affixing stamps and for sealing 10 envelopes.

One object of the present invention is to provide a device by which a stamp can be affixed to an envelop by a single movement 15 of the hand.

Another object of the invention is to provide a device whereby any desired number of stamps can be so affixed at one operation.

Another object of the invention is to provide 20 means for quickly and conveniently sealing an envelop.

A further object of the invention is to provide means whereby the envelop may be first stamped and then sealed by the use of the 25 same device.

Other objects of the invention will appear hereinafter.

Referring to the drawings:—Figure 1 is a perspective of the device showing the manner 30 of using the same in stamping an envelop. Fig. 2 is a perspective showing the manner in which the device is used in sealing an envelop.

Fig. 3 is a vertical section on the line x^5-x^3 in Fig. 1. Fig. 4 is a trans- 35 verse section on the line x^4-x^4 in Fig. 3.

Fig. 5 is an inverted plan of the stamp retaining means. Fig. 6 is a perspective of the means for controlling the stamp feed. Fig. 7 is a vertical section of the inlet valve 40 for controlling admission of air to the water reservoir.

The device comprises a handle member 1 formed as a flat tube of convenient size and shape to be grasped by the hand. The tube 45 may be of rectangular cross-section with an upwardly extending flange 2 at each side, thereof, forming between said flanges a channel for the stamps, as hereinafter explained. The handle member is formed below this 50 channel portion with a chamber or tank 3 adapted to contain water, said chamber having, for example, a filling opening 4 closed by a plug 5. Said plug may have a push button

valve 6 normally held closed by a spring 7 so as to enable air to be admitted from time to 55 time by the pressure of the finger on the push button, thereby allowing water to escape more freely from the tank.

The moistening device consists of a roller or cylinder 9 of felt or other suitable absorbent material mounted to turn on a tubular arm 10 extending beneath and parallel to the bottom of the handle member 1, said arm being L-shaped with its upwardly extending portion 11 communicating with the water 60 chamber 3 in the handle member 1. The tubular arm 10 is perforated as at 12 to allow escape of water from the chamber into the absorbent roller 9. Said roller 9 may have a perforate metal core 13 running on the arm 10. 70

The handle member 1 has forwardly extending side walls 15, at the forward end of which is journaled the shaft 16 of a pressure roller 17. Said pressure roller is preferably faced with rubber or other elastic material 75 and is so formed and arranged that its under or pressure portion extends below the level of the bottom of the handle member 1. A supplementary pressure roller 18 may be provided on the same shaft 16, said supplementary roller being located externally of or beyond one of the side walls 15 aforesaid. Rollers 17, 18 may turn independently on shaft 16.

A stamp retainer 20 extends forwardly 85 from the forward end of the top of the water chamber 3 and extends under the pressure roller 17, said retainer being formed as a sheet metal plate or tongue extending downwardly and forwardly in a convex curve and 90 bending abruptly upwardly at its end to form a stop 19 for arresting the forward movement of the stamps, sufficient space being left between the end of this retainer or stamp and the surface of the pressure roller 95 to enable a single thickness of paper, or a single stamp, to pass at a time.

Feed controlling means 21, consisting of a sheet metal plate bent in channel shape, is pivoted intermediate its ends by pivots 22 100 to the side walls 15 of the handle member extension and has at its forward end two fingers 23 which extend forward at each side of the forward end of the retainer 21 and are adapted to rest against the surface of the 105 pressure roller when this forward end is

2

raised. A finger piece 25 formed as a lateral projection at the rear end of this feed controlling means enables operation of this feed controlling means by the user's finger.

5 The device may be used with a bunch or package of stamps, with a single stamp or with a ribbon or strip of undetached stamps. In using the device with a strip of undetached stamps, the strip is placed with its forward 10 end on top of the feed controlling member 21 in the space between said member and the pressure roller 17, said strip extending on top of the feed controlling member 21 and on top of the handle member 1 and being retained 15 laterally within the channels formed by the side flanges of the said feed controlling member and the handle member. The handle member 1 is grasped by the hand substantially as shown in Fig. 1, so that pressure 20 may be conveniently applied to the finger piece 25 of the feed controlling member by placing the forefinger thereon as shown. The stamp is affixed by first running the moistening roller over the corner portion of 25 the envelop, indicated at 26, which is to receive the stamp, and then by the same motion drawing the pressure roller over said portion and simultaneously pressing a finger on the finger piece 25 of the feed controlling 30 means 21, thereby causing the foremost stamp to be pressed against the roller sufficiently to enable the roller to catch it and draw it forward by friction. As the stamp passes forward under the roller it is immediately pressed by the roller against the already 35 moistened surface of the envelop, so that the same roller in pressing on the stamp serves to feed it forward and to affix it to the envelop. When one stamp has been thus 40 affixed it may be separated from the strip by placing a finger of the other hand on the stamp and drawing on the handle member 1 with a slight twisting action to part the stamp strip along the first line of perforations.

45 If more than one stamp is required it is only necessary to moisten a correspondingly long space and allow the stamps to pass out and be pressed on the envelop before tearing off the strip.

50 In using the device with loose stamps, said stamps are placed one on top of the other in the space between the feed controlling member and the pressure roller and the friction of the pressure roller when the feed controlling 55 member is operated by the finger piece 25, as above described, draws forward the topmost stamp, the retaining stop 19 preventing the remaining stamps from passing forward until the top has been removed. The stamp so 60 drawn forward is affixed by the pressure of the pressure roller, as above described.

In using the device for sealing an envelop the moistening roller is inserted under one end of the flap of the envelop indicated at 65 27 in Fig. 2, and by then drawing the device the

entire length of the envelop and keeping the moistening roller under the flap the gum on the lower face of the flap is moistened and immediately thereafter the pressure rollers 17, 18 passing over the flap serve to press it down 70 on the body of the envelop 26 thereby sealing the envelop, the two pressure rollers providing an extension of roller surface beyond the width of the moistener, which is necessary to insure pressure on the entire flap.

The tubular member 10 has a pointed nose 29 to enable convenient insertion of the moistening member under the flap without catching on the flap.

What I claim is:

1. A stamp affixing means comprising a handle member, a moistening device carried thereby, a pressure roller carried by the handle member, means for supporting stamps on the handle member and feed controlling means for pressing the stamps against the pressure roller to cause the same to be fed forward by the motion of said roller.

2. A stamp sticker comprising a handle member formed with a water chamber, a moistening device beneath the handle member, means for connecting said moistening device to the water chamber in the handle member, a pressure roller supported on the handle member and means for supporting stamps in proximity with said pressure roller, said means being movable to bring the stamps into frictional contact with the pressure roller to enable the same to be fed forward by rotation of the pressure roller.

3. A stamp sticker comprising a handle member formed with a chamber for containing water, a moistening device beneath the handle member provided with means for supplying the same with water from the water containing chamber, a pressure roller supported on the handle member, feed controlling means movably mounted on the handle member and having a stamp supporting portion extending in proximity to the pressure roller to cause frictional engagement of the stamps with the pressure roller, and a stamp retaining stop connected to the handle member and extending in proximity to the pressure roller.

4. An envelop sealer comprising a handle member formed with a water chamber, a tubular arm communicating with said water chamber and having a portion extending beneath said water chamber, a moistening roller rotatably mounted on said tubular arm, said tubular arm being perforated to allow access of water to said moistening roller, and a pressure roller rotatably mounted on the handle.

5. An envelop sealer comprising a handle member formed with a water chamber, a tubular arm communicating with said water chamber and having a portion extending beneath said water chamber, a moistening

roller rotatably mounted on said tubular arm, said tubular arm being perforated to allow access of water to said moistening roller, and pressure roller means rotatably mounted on the handle, said pressure roller means extending beyond the moistening means.

In testimony whereof, I have hereunto set my hand at Los Angeles, California, this 4th day of November 1908.

JOHN T. F. BAEYERTZ.

In presence of—

ARTHUR P. KNIGHT,
FRANK L. A. GRAHAM.
